REMOTE CONTROLLED PAPER CARRIAGE FEED MECHANISM

Hans Bringer, Hans Buschmann, and Willy Schellig, Köln, Germany, assignors to Exacta Euromaschinen Gesellschaft m. b. H., Köln-Deutz, Germany

Application February 7, 1952, Serial No. 270,308

8 Claims. (Cl. 235—60.42)

The invention refers to cash registers, calculating, book-keeping or similar machines provided with a principal and at least one secondary printing mechanism.

Machines of this type serve for the preparation of calculatory, statistical or bookkeeping papers or for the registration of booking items and extracts from the same, respectively. While the total accounts are registered by the principal printing mechanism, the secondary printing mechanism or mechanisms will simultaneously furnish extracts.

With printing office machines of this kind methods are known whereby either the paper or the printing members are moved in accordance with the mode of registration desired, i. e. to print the accounts with the necessary spacing in the columns provided. This relative movement, however, may be performed by the secondary printing mechanisms only in the manner for which the machines are constructed to begin with; thus with the familiar machines of this kind extracts may be prepared only in previously determined manner by the secondary printing mechanisms allowing adjustment within very narrow limits only. In actual practice, however, frequently the necessity presents itself to effect entries on the entry sheets to be prepared by the secondary printing mechanism in a definite form corresponding to changing requirements in commercial practice and bookkeeping, which up to now has not been possible.

The present invention offers this possibility for the first time and does away with the shortcomings of the absolute dependence of the secondary printing mechanism from the principal printing mechanism, in such a way, that machines of this type may be employed hereafter in many novel ways.

In accordance with the present invention, the secondary printing mechanism, or mechanisms, are actuated in such a way by the principal printing mechanism or main machine that the arrangement and/or the selection of the records to be printed by the secondary printing mechanisms may be effected according to choice. By preference, electrical or electromagnetic controlling means are employed for that purpose.

The arrangement in accordance with the invention has been made in such a way that the means for the control of the secondary printing mechanism, or mechanisms, are dependent from elements of the main machine and freely selective adjusting means. At the same time, the secondary printing mechanisms may be made for engagement or disengagement, according to choice.

Practical execution is effected in such a way that the actuation of the printing mechanism as well as the relative movement of the printing mechanism with regard to the paper of the secondary printing mechanisms are effected by controlling elements of the main machine in dependence from the selection of the adjusting means.

It is recommended to employ for that purpose a function controlling cylinder on the main machine, into which adjusting members are inserted in so many rows as the carriage of the principal printing mechanism or of the

2

secondary printing mechanism, or mechanisms, respectively, is expected to provide columns.

In similar fashion, the spacing of the lines of the secondary printing mechanism is effected in dependence from the position of the principal printing mechanism and of the function controlling cylinder and of the adjusting members that may be inserted in the latter in different positions.

For that purpose, a line spacing shaft and a dial for selection connected therewith may be provided on the secondary printing mechanism which by way of a clutch engageable and disengageable in dependence of the principal printing mechanism may be connected with the drive and stopped in dependence of the adjusting means.

Furthermore, it will be possible also by way of the dial for selection to actuate a cutting mechanism serving to cut off individual record sheets from a feed roller. For that purpose, the cutting mechanism will be adjusted by preference in such a manner that during any particular operation forms or slips of identical length are cut off the roller. It is also possible, however, to make the length of the record sheets to be cut off dependent upon the number of lines recorded, i. e. to cut off strips of changing lengths according to the scope of any particular record.

In the drawings, the most important individual elements of the machine in accordance with the invention are represented by way of example and that, for reasons of better presentation, in perspective view. The exterior shape and arrangement of the individual mechanisms of the machine is optional. The secondary printing mechanisms may be constructed to form an integral part of the main machine or they may be independent machines even to the extent of permitting their setting-up in rooms apart from where the principal printing mechanism is situated if the transmission of the controlling energy is effected electrically.

Fig. 1 shows schematically the connection of the principal printing mechanism with the secondary printing mechanism and the other mechanisms of the machine;

Fig. 2 shows the carriage of the secondary printing mechanism with its corresponding driving means;

Fig. 3 shows various actuating and blocking mechanisms for the columnar travel;

Fig. 4 shows the dial of selection for line spacing, with its corresponding actuating elements;

Fig. 5 shows the arrangement of the contact means on the principal printing mechanism for the control of the secondary printing mechanisms;

Fig. 6 shows the adjusting means for the secondary printing mechanism, and

Fig. 7 shows a cutting mechanism for cutting off from sheets from a feed roller.

All figures have reference to an automatic accounting machine. However, similar arrangements may also be employed with other recording machines.

In the mode of execution of the invention schematically shown in Fig. 1, a principal printing mechanism D1 is provided and a paper carriage W1 cooperating therewith and being laterally movable into a number of column positions.

A secondary printing mechanism D2 which may be located in an optional distance apart from the principal printing mechanism cooperates with a paper carriage W2 adjustable into several, e. g. four, column positions.

The lateral movement of the paper carriage W2 in relation to the carriage W1 will be controlled by means of a function controlling unit in form of a cylinder 1, in such a way, that each column position of the carriage W1 will have allotted to a distinct column-position of carriage W2. For this purpose said cylinder 1 is mechanically connected to carriage W1 by means of a rack W

and gears 1' in such a way, that each column position of carriage W1 corresponds to one of the turning positions of cylinder 1. In each turning position four controlling elements 2 detachably fixed on the cylinder 1 and corresponding to four column-positions I to IV of carriage W2 cooperate with feeling levers 3, which influence contacts or the like, operating the device for moving carriage W2 into the column-positions by means of electrical connections. In addition, function controlling cylinder 1 is provided with detachably controlling elements 5 actuating contacts 7 by way of feeler levers 6 for the line spacing on the secondary printing mechanisms.

After carriage W2 has been adjusted into that column position which is allotted to the adjusted column of carriage W1 in accordance with the controlling elements 2 the printing type members 51 of the secondary printing mechanism D2 have to be adjusted by means of longitudinal movement, to the same figures or signs to which the type members 50 of principal printing mechanism D1 having been positioned.

With printing mechanisms D1 and D2 being arranged close together the type members 50 and 51 allotted to each other may be connected with each other in a direct and mechanical way. In the mode of execution shown in which the printing mechanisms are thought separated from each other, adjustment of the type members 51 (Fig. 1) is performed by electrical means whereby below the contacts 50' (Fig. 5) fixed to the individual type members 50 a contact slide 45 is passed along a cross member 51' (Fig. 1) being moved the same distance by mechanical or electrical connection means 46, 46' when a cross member 51' will release the spring actuated printing members 51.

In the moment in which one of the contacts 50' is closed an electro-magnet 54 allotted to the corresponding type member 51 will be excited by means of connections X and induced to arrest the type member 51 in such a way that upon further movement of cross member 51' said type member 51 cannot be moved further on.

A selecting mechanism S is provided too in the system of connections for the control of the column-positions and the line switching by means of which the mentioned controls may be additionally influenced.

Now the individual mechanism of the machine will be described more in detail.

Carriage W2 (Fig. 2) of the secondary printing mechanism which is slidably supported in a known manner is moved by a driving mechanism 10 equipped with a reversing clutch 11 by way of rack 9. In this way, drive gear 14 may be actuated to the right or to the left alternatively and depending upon whether magnet winding 12 or 13 (see also Fig. 1) is being excited. Line spacing shaft 15 drives the platen 18 over corresponding bevel gears 16 and a screw drive 17. The drive of the line spacing gear is effected over a clutch 19 which may be actuated through a magnet 20 through its armature 21. Limiting stops I to IV are arranged on part 8 (Fig. 2) of the paper carriage W2 each allotted to one of the four column positions.

Arrangement and functioning of limiting stop I may be gathered from Fig. 3; the others are in principle of identical construction. In this case, limiting stop I is provided with a switching nose 22 which actuates contact springs 25 and 26 through control rod 24 by way of a feeler lever 23 when the carriage is moved, thereby closing or opening the corresponding contact. In slot 27 of the limiting stop, control means 28 may be inserted to actuate the corresponding contact 30 by way of feeler lever 29. With a lower nose 31 of the limiting stops blocking levers 32 and 33 are in cooperation which may be actuated by one magnet each 34 or 35 (see also Fig. 1), respectively, depending upon the direction of movement of the carriage.

According to Fig. 4, shaft 15 actuates a selective dial 75

38 for line spacing by way of an appropriate gearing 36, 37, the dial being provided on its periphery with one or a plurality of detachable controlling bits 39 cooperating with a triple-armed notch-engaging lever 40. This lever is actuated by armature 41 of magnet 42 (see also Fig. 1) its feeler nose 40a engaging controlling bit 39 while feeler nose 40b will lean against a pawl 43a on control lever 43 which in turn can actuate a retaining contact 44 for clutching magnet 20 (Figs. 1, 2).

Fig. 5 illustrates the arrangement of the contact mechanisms within the principal printing mechanism for the adjustment of the type members of the secondary printing mechanism. Contact carriage 45 driven by gears 46 slides along a rigid feeding plate 47 provided with contact springs 48 sliding on feeler strips 49 on the contact carriage. Depending upon the position of the contact carriage 45 and the contact bridges, respectively, springs 48 may be bridged over, thereby initiating switching operations to the secondary printing mechanism by way of connections X (Fig. 1).

In Fig. 6 an adjusting mechanism for the type members 51 of the secondary printing mechanism is illustrated which provides recesses corresponding in number to the number of their printing signs and which cooperate with pawls 52 which are released to enter said recesses by the armature 53 of their magnet 54 as soon as the latter being excited over connections X (Fig. 1).

Finally, in Fig. 7, a cutting device is illustrated which may be provided for cutting off accounting sheets on the principal and/or secondary printing mechanism in case a feed roller is employed. The drive of the cutting device is effected from the drive disc 55 by way of screw spindle 56 permitting to slide a carriage 57. This carriage is supported at 58 and carries a cutter 60 on shaft 59, said cutter being turned when the carriage is moved laterally through gear 61 in mesh with toothed rack 62. End contacts 63 for reversing the drive are provided on the frame of the cutting device. This cutting device may be actuated on dependence of line spacing for the paper carriage W1 or W2, e. g. by means of the selective dial 38 (Fig. 4) with the use of detachable controlling bits and levers similar to the bit 39 and lever 40.

The cooperation of the individual elements of the equipment is as follows:

The function controlling cylinder 1 (Fig. 1) arranged within the main machine and moved in conjunction with the paper carriage of the principal printing mechanism will close according to its position and the shape of the control organs 2 one of the contacts 4 over the feeler levers 3 for column adjustment of the paper carriage of the secondary printing mechanism. Likewise, by the positioning of the carriage W2 of the secondary printing mechanism one of the limiting stops I to IV will open one of the contacts 30 by way of one of the feeler levers 29 (Fig. 3). If, for instance contact 4 for column II of the carriage W2 has been closed and the carriage is to be found in column II the corresponding contact of the limiting stop II is opened. The circuit is broken, the reversing clutch 11 (Fig. 2) for the movement of the carriage (Figs. 1 and 2) and the blocking lever 32 and 33 respectively for the limitation of the carriage movement will not be actuated. If, on the other hand, carriage W2 of the secondary printing mechanism is situated for instance on column I, and the function controlling cylinder 1 has actuated the contact 4 for column III while feeling, conformity will be extant no longer, with the result that the corresponding contact 30 of the limiting stop III is closed. The corresponding blocking lever 32 or 33 (Fig. 3) for the limitation of the carriage movement and the reversing clutch 11 will be engaged through their magnets 34 and 35, respectively, and 12 and 13, respectively. Carriage W2 (Fig. 1) of the secondary printing mechanism will thereupon run to a point where its position will coincide with the one demanded by the

principal printing mechanism; thereby the corresponding contact 30 will be opened again by means of the control means 28 of the limiting stop III in such a way that the magnets become again currentless, and the blocking lever 32 blocking anew whereby clutch 11 is simultaneously disengaged.

The above mentioned selecting mechanism S, the chief object of which is to control the circuits of the magnets 12, 13 (Fig. 2) for the reverse clutch 11 and the magnets 34, 35 for actuating the blocking levers 32, 33 (Fig. 3) provides four magnets a, b, c, d (Fig. 1) mounted on the frame of the selecting mechanisms each of which is connected by conductions A with one of the contacts 4 over one of the contacts 30 (Fig. 3), in such a way, that magnet a (Fig. 1) belongs to column position I, magnet b to column position II, magnet c to column position III and magnet d to column position IV of the paper carriage W2.

The magnets "a to d" respectively can only be excited when both of the allotted contacts 4 and 30 are closed. Below the magnets a to d a slide s1 is shiftable mounted on the frame of the selecting mechanism which carries two levers f, g on a common fulcrum e. Levers f, g represent armatures for the magnets a to d and are attracted by that of the magnets a to d, the circuit of which being closed by the contacts 4 and 30. Slide s1 carries also two contacts h and i each cooperating with end of the lever f or g, respectively, each contact will be closed by its lever end when the appertaining lever f or g is attracted by one of the magnets a to d; the contact h closes the circuit for the magnet 12 (Fig. 2) and the contact i the circuit for the magnet 13 of the reversing clutch 11. Further the magnets 34 and 35 (Fig. 3) respectively for the blocking lever 32 or 33 are connected with the contacts h and i. The circuit of contacts h and i runs over the contact 25 (Fig. 3) actuated by feeler lever 23 in such a way, that the magnets 34, 35 respectively and magnets 12, 13 respectively can only be excited when the paper carriage is in a column position, as shown in Fig. 3, provided that one of the contacts h and i has been closed.

Slide s1 (Fig. 1) carries a rack r with which the armatures of magnets k and l cooperate which are mounted on the frame of the selecting mechanism S said armatures pivotally mounted on the frame of the selecting mechanism acting as pawls in order to move the slide in the one or the other direction each time they are attracted and then moved back by their springs. By means of the rack r and by exciting the magnet k the slide will be moved in this way by means of the armature of magnet k to the left and by exciting the magnet l the slide will be moved to the right. The circuits of the magnets k and l runs over the contact 26 (Fig. 3) and over the contacts h and i respectively, so that when the paper carriage W2 is leaving a column position and lever 23 (Fig. 3) falls off the nose 22 contact 26 being closed closing the circuit of the magnet k or l, respectively whereby the same attract their armatures which cooperate with the rack r, hence the slide s1 will move one step to the right or left, opposite to the direction of the movement of the paper carriage W2. This movement continues from column position to column position in the same direction till the column position corresponds to the adjusted control member 2 (Fig. 1). In this case the contact 30 is opened when the contact 30 runs up on the allotted control means 28 and none of the magnets a to d can be excited. Thereby the fulcrum e (Fig. 1) of the slide s1 lies below that magnet a to d which belongs to the attained column position. When, as in the already mentioned instance the carriage W2 is found in column I and is to be adjusted to column III according to the set controlling member 2 (Fig. 1) the circuit for the magnet c is closed by the contact 4 allotted to the control element 2 and the third contact 30 from above in Fig. 3. The excited magnet c

(Fig. 1) attracts lever g which closes contact i, so that the magnets 12 and 35 are excited and the carriage will be moved to the right. Thereby feeler lever 23 (Fig. 3) falls off the nose 22, whereby the contact 25 is opened while contact 26 is closed. Armature 33 is released and moves into the way of the nose 31 of the following limiting stop II for stopping the carriage again. By the closing of the contact 26 magnet l (Fig. 1) is excited over contact i whereby the slide s1 is moved one step to the right. When the carriage W2 has attained column position II the same operations repeat, and on attaining the position III the movement of the carriage will cease because that contact 30 which is connected with the contact 4 of the set control member 2 (Fig. 1) is held open by the control means 28 which is found on the limiting stop III in the third slot 27 from above.

For spacing the lines, contacts 7 (Fig. 1) have been provided by which the magnet 20 (Fig. 2) for spacing on and off of the line switching clutch 19 can be actuated. When exciting magnet 20, the end of armature 21 is lifted off nose 19a of clutch 19, the clutch becomes engaged and the line spacing shaft 15 is turned. With each revolution, the selecting dial 38 is turned one step ahead by way of gearing 36, 37 (Fig. 4). If now contact 7 (Fig. 1) is closed, magnet 42 by way of connection C will be excited attracting its armature 41 (Fig. 4) whereby the triple-armed lever 40 is released and swung under the influence of its spring (not shown) in counterclockwise direction leaning with its arm 40b against the pawl 43a of the control lever 43. Upon turning movement of the selecting dial 38 control lever 43 is turned in clockwise direction by the teeth of the dial lowering pawl 43a, so that the hooklike end of the arm 40b, can snap over pawl 43 in order to hold down the control lever 43 in a position in which contact is closed in such a way that magnet 20 (Figs. 1 and 2) over connection E will receive permanent current and the line spacing shaft will be revolved until the retaining contact 44 (Fig. 4) is released again. This will be the case every time a controlling bit 39 on selecting dial 38 lifts the lever arm 40a. In this manner, contact 44 will be released and notch-engaging lever 40 blocked by magnet 42.

The actuation of the type members 50 (Fig. 5) of the principal printing mechanism and of the type members 51 (Fig. 6) of the secondary printing mechanism or mechanisms takes place synchronously. While keys or other abutments control the way of value of adjustment of the type members 50 of the main machine, this way or value will be transferred to the members 51 of the secondary printing mechanism or mechanisms. For this purpose the corresponding magnet 54 (Fig. 6) will be excited by the movement of the slide 45 (Fig. 5) and by means of the contact bridge 50', the slip springs 48 and the contact strips 49, whereby the armature 53 is freeing lever 52, entering a recess of its member 51 which follows its spring, whereby the member 51 is locked in a position corresponding to the value the corresponding member 50 of the main machine having been adjusted.

A cutting device (Fig. 7) may be provided on the principal as well as on the secondary printing mechanism, the drive by way of driving disc 55 and screw spindle 56 again allowing of being switched on and off by a magnetically actuated clutch similar to clutch 19 (Fig. 2).

Operation is preferentially effected with the aid of a switch button from the main machine, it being possible to actuate the cutting blades on the principal and secondary printing mechanisms either separately or simultaneously.

What is claimed as new is:

1. In a calculating machine of the class described, a principal printing mechanism comprising a set of principal type members, a principal paper carriage, cooperating therewith, means adapted to relatively position said

set of principal type members and said principal carriage, comprising means for line spacing and means for columnar adjustment, a secondary printing mechanism comprising a set of secondary type members, a secondary paper carriage, and means adapted to relatively position said set of secondary type members and their secondary paper carriage comprising means for line spacing and means for columnar adjustment, a function control unit having detachable control members, means adapted to adjust said control unit in correspondence to the relative adjustment between said principal paper carriage and said set of principal type members, and connecting means between said detachable control members and said secondary printing mechanism, whereby the arrangement of printed matter on the records to be printed by the secondary printing mechanism may be effected freely.

2. In a machine according to claim 1, and means adapted to allot for each column position of the principal printing mechanism one distinct column position of the secondary printing mechanism freely selectable by adjusting said detachable control members of said function control unit.

3. In a machine according to claim 1, and means adapted to allot for each column position of the principal printing mechanism one column position of the secondary printing mechanism, said means for adjusting said secondary paper carriage consisting of limiting stops, one for each column position arranged on the secondary paper carriage, each having detachable control means, feeling members cooperating therewith, connecting means between said feeling members on said function control unit and said detachable control members, whereby the secondary paper carriage is moved to the right or to the left when the control means on the secondary paper carriage engaged by said feeling members do not correspond to said adjusted control members on said function control unit.

4. In a machine according to claim 1, said control unit being a rotatable cylinder, feeling members adapted to cooperate with said detachable control members, embodying a part of said connecting means between said detachable control members and said secondary printing mechanism, said detachable control members being arranged on said cylinder in longitudinal and circumferential rows, and means adapted to allot each longitudinal row to one of the column positions of the principal paper carriage, and each circumferential row to one of the column positions of the secondary paper carriage.

5. In a machine according to claim 1, said detachable

control members being adapted to actuate distinct line spacing of the secondary printing mechanism according to the column positions of the principal paper carriage.

5 6. In a machine according to claim 1, said line spacing means for the secondary paper carriage comprising a selecting dial, controlling bits detachably mounted on said selecting dial adapted to control the number of line spacings.

10 7. In a machine according to claim 1, said detachable control members being adapted to actuate distinct line spacing of the secondary printing mechanism according to the columnar movement of the principal paper carriage, said line spacing means comprising a drive clutch adapted of being made effective according to said detachable control members, a selecting dial, controlling bits detachably mounted on it, said selecting dial being moved in accordance with said line spacing for the secondary printing mechanism, a switching lever cooperating with said controlling bits adapted to make ineffective said coupling when actuated by one of said controlling bits.

15 8. In a machine according to claim 1, means adapted to adjust said type members of said secondary printing mechanism in accordance to the adjustment of the principal type members, comprising contacts arranged on the principal type members, magnets each allotted to one of said secondary type members, locking levers cooperating with said magnets and said secondary members, counter contact means cooperating with said contacts of the principal type members, a cross member holding said secondary type members against the stress of their springs and means for synchronously moving said counter contacts and said cross member, whereby the magnet of 20 a secondary type member being excited and the secondary type member being stopped by means of its locking lever when the allotted counter contact reaches the contact of the allotted principal type member.
